MAURITS J. SANDIN, OF WILKINSBURG, AND JOHN B. MACNEILL, OF PITTSBURGH, PENNSYLVANIA, ASSIGNORS TO WESTINGHOUSE ELECTRIC & MANUFACTURING COMPANY, A CORPORATION OF PENNSYLVANIA.

REFILLABLE FUSE.

Application filed January 12, 1920, Serial No. 351,000. Renewed February 2, 1924.

To all whom it may concern:

Be it known that we, MAURITS J. SANDIN, a citizen of the United States, and a resident of Wilkinsburg, in the county of Allegheny and State of Pennsylvania, and JOHN B. MACNEILL, a citizen of the United States, and a resident of Pittsburgh, in the county of Allegheny and State of Pennsylvania, have invented a new and useful Improvement in Refillable Fuses, of which the following is a specification.

Our invention relates to fuses and particularly to refillable cartridge fuses.

One object of our invention is to provide a cartridge fuse having means for so controlling the escape of arc gases as to prevent damage to the cartridge, to ensure a proper relatively high internal pressure to reduce the arc and to so cool the escaping gas as to prevent the emission of flame.

Another object of our invention is to provide a cartridge fuse adapted for use with the standard fuse-terminal clips that shall employ one or a plurality of interchangeable members to form an auxiliary cooling-chamber or chambers therein of predetermined cooling-surface area for a fuse or fuses of given capacity.

Another object of our invention is to provide means whereby certain relatively-small, normally-loose parts of a cartridge fuse shall be so permanently associated with other relatively-large parts as to facilitate their manipulation and reduce the likelihood of the loss thereof.

The present standard forms of cartridge fuses and the stationary terminal clips therefor are of certain dimensions and constructions for given rating. These features have resulted from relatively long practice during which the proper proportions and forms have been developed, but the features of preventing the disruption of certain parts and the emission of flame have not, to the best of our knowledge, been developed to very high degrees of efficiency and economy.

This has probably been due to the limitations imposed by the forms and dimensions which were arrived at in the attempts to obtain effectiveness in other features, such as conductivity and mechanical strength.

It has been found that a high internal pressure is desirable to facilitate extinguishing the arc but this pressure must not be too

high because disruption of the cartridge and other damage and loss may ensue.

Further, the emission of flame, even though small in amount and extending to only a short distance from the cartridge, is an undesirable feature.

Reference may be had to copending application, Serial No. 350,948, filed January 12, 1920, by M. J. Sandin and assigned to the Westinghouse Electric & Manufacturing Co. in which is disclosed a cartridge fuse for accomplishing substantially the same results but which is of different operation and construction.

In practicing our invention, we provide a renewable cartridge fuse constructed in accordance with standard requirement in which there shall be definite relations between the internal pressure, the rate of gas escape and the degree to which the gas is cooled before it reaches the outer air or surrounding objects.

This is accomplished, irrespective of space and other limitations of the standard cartridge fuse, and, at the same time, permits the fuse to be manipulated in a simple and expeditious manner.

Figure 1 of the accompanying drawings is a side view, partially in elevation and partially in section, of a cartridge fuse embodying our invention; Fig. 2 is a plan view, partially in section, of a portion of one end thereof; Figs. 3, 4, 5, 6, 7 and 8 are detail views of various washers embodied in the device of Figs. 1 and 2; Fig. 9 is a view, similar to Fig. 1, of a modified form of fuse cartridge embodying our invention, and Figs. 10 and 11 are detail views of a modified form of washer employed in the device of Fig. 9.

In general, our device comprises an insulating casing 1, end ferrules 2, terminal blade members 3 and a fusible element 4.

The members 3 have outer portions 5 for cooperation with the usual standard fuse clips (not shown) and smaller inner-end portions 6 to which the element 4 is attached, as by bolts or screws 7 and nuts 8.

Washers 9 and 10, preferably of diameters to snugly fit the interior of the casing 1 have apertures 11 and 12, respectively, that conform to the smaller end 6 of the member 3, are placed on the end 6 against the end 5 and are swaged or otherwise se-

cured in position, as indicated by upset portions 13. A washer 14, of larger diameter than the interior of the casing 1, has an aperture 15, permitting it to be slipped 5 over the portion 5 of the member 3, and a positioning lug 16 for insertion in a notch (not shown) in the end of the casing.

The washer 14 is secured to the washers 9 and 10 by screws 17 that have intermediate portions 18 of reduced diameter opposite which the washer 14 has upset or swaged portions 19 to prevent the withdrawal of the screws 17 through the washer 14. Thus, the screws 17, while readily 15 turnable in the washer 14 to permit the latter to be attached to and detached from the washers 9 and 10, may not be separated from the washer 14. An inwardly-extending flange 20 on the ferrule 2, that is preferably threaded to the casing 1, engages the washer 14 to hold the terminal parts in position.

The washer 10 has portions 21 and 22 on its faces that are countersunk or depressed 25 except at the perimeter of the washer, at narrow portions surrounding the aperture 12 and at portions surrounding the holes 23 for the reception of the screws 17. The portions 21 and 22, in cooperation with the washers 9 and 14, provide gas-cooling chambers of sufficient area to so cool the gases as to prevent the emission of flame from the cartridge.

To provide communicating passages from 35 the interior of the fuse casing to the gas chambers between the washers 9 and 10, the washer 9 is provided with openings, preferably notches 24 that extend from the perimeter to points on the diameter thereof 40 within the rim of the washer 10. Apertures 25 in the reduced central body portion of the washer 10 are angularly displaced about the axis of the cartridge with respect to the notches 24 and serve to conduct arc gases to the chamber between the washers 10 and 14. From the chamber between the washers 10 and 14, the gases are conducted to the outer air through 45 apertures 26 in the washer 14 that are angularly displaced with respect to the apertures 25 in the washer 10.

In operation, when the element 4 is volatilized, a quantity of gas, under relatively great pressure, is generated. If the escape 55 passages are too restricted, the force of this gas will rupture some portion of the cartridge. It is, therefore, imperative that the pressure be reduced. On the other hand, a relatively high pressure is desirable 60 to assist in quenching the arc. The mean between these opposing factors lies in having the escape passages of a definite predetermined size for a fuse of given capacity. Also in a fuse of given capacity 65 and therefore of certain flame-generating

property, a definite amount of cooling area must be provided to prevent any flame reaching the exterior of the cartridge. It is not sufficient to merely provide openings to permit the escape of gas. The openings 70 should be in accord with the explosive force, in which case the arc is held to a minimum, at its inception, for a fuse of given capacity and a cartridge of given strength. The area of the cooling surfaces at the portions 75 21 and 22 of the washer 10, in co-operation with the washers 9 and 14, is then of a predetermined size to cool the flame of this predetermined arc, there being definite relations between internal pressure, rate of escape of the gas and the amount of cooling. 80

The device shown in Fig. 9 is similar to the above described device in that it employs the washers 9, 10 and 14 in the same manner but it also utilizes a washer 27 that 85 is countersunk or depressed on one face only at its central portions 28 and is disposed between the washers 10 and 14. This provides additional cooling area for a fuse of higher current-carrying capacity that 90 generates a greater amount of gas. Compensation for the higher explosive force may be attained by increasing the number and sizes of the openings 25 and 26.

While we have shown and described particular forms of our invention, it is obvious that the parts thereof may be changed and used in various other combinations and relations, without departing from the spirit and scope thereof, as set forth in the appended claims. 95

We claim as our invention:

1. A cartridge fuse comprising three members engaging in relatively-broad-surface relation, the central one of which has its perimeter and intermediate portions of different thicknesses to provide a gas-cooling chamber between it and the other members. 105

2. A cartridge fuse comprising three members engaging in relatively-broad-surface relation, the opposite surfaces of the central one of which are countersunk to provide gas-cooling chambers of relatively great area between said members. 110

3. A cartridge fuse comprising a terminal washer having an opening and a second washer having a countersunk surface portion engaging said terminal washer, said countersunk portion constituting a gas-cooling chamber between said washers, and said opening constituting a communicating passage between the outer surface of the terminal washer and said chamber. 115

4. A cartridge fuse comprising a terminal washer having notched periphery and a second washer having a countersunk surface portion engaging said terminal washer, said countersunk portion constituting a gas-cooling chamber between said washers, and said notch constituting a communicating pas- 120 125 130

sage between the outer edge of the terminal washer and said chamber.

5. A refillable cartridge fuse comprising a terminal washer having a notched periphery, 5 and a second washer having a countersunk surface portion engaging said terminal washer and an opening through said countersunk portion, the latter portion constituting a gas-cooling chamber between said washers 10 and the said notch, and said opening constituting communicating passages to the interior of the washers.

6. A cartridge fuse comprising a casing, a terminal member therefor, an inner washer 15 on the terminal member having a peripheral notch, an intermediate washer on the terminal member having an opening therethrough and a countersunk face communicating with said notch, an apertured outer washer on the 20 terminal member engaging the end of the casing, means for holding said washers together, and means for holding the washers and the terminal member in position with respect to the casing, the arrangement providing a unitary removable structure of substantially minimum length having a tortuous 25 gas-escape path and a gas-cooling chamber therein.

7. A refillable cartridge fuse comprising 30 a casing, an end ferrule therefor, a knife-blade terminal member, a plurality of washers on said terminal member, one of which is larger than the interior diameter and engaged to the end of the casing by said 35 ferrule, and irremovable means on said larger washer for holding all of said washers together.

8. In a refillable cartridge fuse, the combination of a casing, terminal members 40 therefor, a fusible element, means for removably securing said element to the terminal members, means rigidly secured to the terminal members for directing arc gases in

a path transversely of the casing, and removable means independent of the said securing means and detachably secured to the second said means for aligning and centering the terminal members and means for preventing longitudinal movement of the last said means. 45

9. A refillable cartridge fuse comprising a casing, a knife-blade terminal member, a member embracing the blade member for positioning the latter with respect to the casing and a second member embracing the 50 blade member for securing said positioning member to the blade member, one of said members having a depressed surface portion to provide an enclosed gas-cooling chamber 55 in the casing.

10. A cartridge fuse comprising a tubular casing, a terminal blade-member provided with a pair of washers having a gas-conducting and cooling chamber therebetween, a third washer removably mounted upon 60 the blade member for positioning the latter with respect to the casing and a ferrule for clamping the removable washer to the casing.

11. A cartridge fuse comprising a tubular casing, a terminal blade member provided with a pair of washers having a gas-conducting chamber therebetween, and secured to the blade member, a third washer removably mounted upon the blade member 75 for positioning the blade member with respect to the casing, a ferrule for clamping the removable washer to the casing and means for preventing separation of the blade member and the removable washer. 80

In testimony whereof, we have hereunto subscribed our names this 31st day of December, 1919.

MAURITS J. SANDIN.
JOHN B. MACNEILL.
